[57] CLAIM

I claim the ornamental design for a golf device, as shown and described.

DESCRIPTION

FIG. 1 is a perspective view of a golf device showing my new design;

FIG. 2 is a side elevational view, the opposite side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.
